UNITED STATES PATENT OFFICE

1,996,028

ELECTRICAL LAMP SOCKET

Rudolf Popp, Valparaiso, Ind., assignor to McGill Manufacturing Company, Valparaiso, Ind., a corporation of Indiana

Application February 2, 1931, Serial No. 512,836

4 Claims. (Cl. 173—354)

My invention relates to an electrical switch and more particularly to a switch for an electric lamp socket.

An object of the present invention is to provide a new and improved socket switch assembly.

A further object is to provide a socket switch assembly in which the screw shell is permanently secured to the base in a simple and inexpensive manner and particularly by the horseshoe terminal.

A further object is to provide a new and improved supporting means for the center contact of a socket switch.

A further object is to provide a device in which the center contact is secured to the switch frame by one of the frame elements.

A further object is to provide a simplified and effective arrangement of the elements of a socket switch.

Other objects and advantages will appear as the description proceeds.

Electrical lamp sockets are used so extensively at the present time that improvements which result in even a small saving in the cost of a single unit, mount to substantial proportions when the sockets are made in large quantities.

Heretofore it has been a common practice to mount a socket switch on a porcelain base and assemble the switch mechanism and screw shell of the socket on the base by means of a pair of long screws passing through the porcelain base and screw shell into the horseshoe terminal.

In accordance with the general features of the present invention, the screw shell of the socket is permanently attached to an insulating plate and the switch mechanism is supported between this plate and a second insulating plate spaced from the first plate by a pair of separating posts which also form a part of the circuit and to one of which the center contact is secured.

Referring to the drawing,

Fig. 1 is a side elevation of a socket switch assembly embodying the invention with the outer casing removed.

Fig. 2 is a right side elevation of Fig. 1.

Fig. 3 is a sectional view taken on line 3—3 of Fig. 1.

Fig. 4 is a sectional view taken on line 4—4 of Fig. 2.

Fig. 5 is a fragmentary section taken on line 5—5 of Fig. 4.

Fig. 6 is a perspective detail view of the horse shoe terminal.

Fig. 7 is a perspective detail view of the pawl for actuating the ratchet wheel, and

Fig. 8 is a plan view of the bridging contact member.

The switch mechanism is mounted between a pair of insulating plates 12 and 13 of any suitable insulating material, which are spaced apart and held in position by a pair of posts 14 and 15, which extend through the plates and are upset at their upper and lower ends to clamp the plates and hold them in position. The plate 13 has a screw shell 16 mounted thereon having an inturned flange 17, lying against the face of the plate. Within the screw shell and overlying flange 17 is a horseshoe terminal 18 having lugs 19, 21, and 22, which are bent at right angles to the plane of the horseshoe terminal and are inserted through openings in the flange of the screw shell and slots 23, 24 and 25 in plate 13. The projecting portions of lugs 19 and 21 are then bent flat against the upper face of the plate to securely clamp the screw shell to the plate, as shown in Fig. 5. 15 Lug 22 is allowed to remain upstanding and is provided with a screw 26 for connecting the horseshoe terminal and screw shell in an electric circuit. This provides a simple and effective means for securing the screw shell to the insulating plate and forms a unit of these members. 20

A U shaped member 27 is supported between plates 12 and 13 and has projections adapted to extend into these plates to hold the member in position. This member is reduced as shown at 30 28, and has a round collar 29 attached to its end upon which a lever 31 is adapted to rock when a tension is applied to chain 32. Lever 31 is connected to a stem 33 by a universal connection, whereby the rocking of lever 31 in any direction 35 will pull the stem to the right as viewed in Fig. 4. Stem 33 is provided with a head 46 and carries a U shaped pawl 43 having arms 44 and 45. Surrounding stem 33 is a helical spring 47 which rests at one end against the U shaped member 40 27 while its other end rests against pawl 43 holding the pawl and stem in extended position, as shown in Fig. 4. A square shaft 34 having reduced cylindrical ends is rotatably mounted between the plates. This shaft has a ratchet 45 wheel 42 provided with a square opening slidably mounted thereon and the arms 44 and 45 of pawl 43 are provided with longitudinal slots in which the ratchet wheel engages, thus positioning the ratchet wheel axially on the shaft. 50 The slot in arm 44 is of such length that when the pawl is moved to the right, as viewed in Fig. 4, the end of the slot will engage a tooth of the ratchet wheel and rotate the wheel as well as the shaft in a clockwise direction. Upon release of 55

the pull applied to chain 32, spring 33 returns the pawl to its normal position and the end of arm 44 is bent at an angle to facilitate its riding over the teeth of the ratchet wheel upon its 5 turn movement. The length of the slot in arm 45 is long enough not to interfere with the rotation of the ratchet wheel.

Upon the upper end of the square shaft a contact carrying member 35 of any suitable insulating material is mounted so as to rotate with the shaft. This contact carrying member has a 10 square opening extending partially therethrough and a circular opening extending from the end of the square opening completely through the member so that when the member is mounted upon shaft 34 it will be held in position against plate 12 on the upper end of the shaft. The contact carrying member has a plurality of teeth which are alternately cut deep and shallow and a bridging contact member 36 is provided, having its 15 contact surfaces turned up so as to over-lie and provide bridging faces upon the shallow teeth. The bridging contact member is illustrated more fully in Fig. 8 and consists of an annular portion 20 36' surrounding shaft 34, and from this annular portion a plurality of arms extend radially to the contacting portions overlying the shallow teeth. The annular portion and arms of this bridging contact member in the assembled 25 device lie between the contact carrying member 35 and the plate 12.

Each of the posts 14 and 15 carries a stationary contact member 37 of resilient material. These 30 contact members are so bent as to have inwardly curved contacting portions lying substantially opposite each other for engaging the movable contact carrying member and have a substantially straight portion, which is re-bent upon itself to give additional resiliency and at the end of the re-bent portions the members are bent at 35 a right angle. These right angle portions are secured in slots provided in posts 14 and 15. When the stationary contact members 37 pass from the deep cut insulated teeth of the contact carrying member to the shallow contact carrying teeth, the drop is small and the tension of the 40 springs is only slightly released, thus preventing re-bound of the stationary contact members when they strike the contact carrying teeth. In 45 one position of the movable contact member both of the stationary contact members will rest upon insulated teeth and in another position of the movable contact member both of the stationary contact members will rest upon and be bridged 50 by teeth having a conducting face, in which position posts 14 and 15 will be electrically interconnected.

The post 14 is provided with a screw 38 for 55 electrically connecting this post to an electric circuit. The post 15 extends through insulating plate 13 into the open side of the horseshoe terminal and has secured thereto an arm 39, which passes through the open side of the horseshoe terminal to a center contact 41. Thus when a 60 lamp is placed in the screw shell and a pair of leads from an electric circuit are connected to lug 22 and post 14, one of the leads goes directly from lug 22 through the screw shell to the lamp while the other lead goes from post 14 through 65 70 the bridging contacts 36 of the switch mecha-

nism to post 15 and thence to center contact 41 and to the lamp. This forms a sturdy and rugged construction, which may be conveniently and economically assembled.

The mechanism for operating the switch just 5 described is more fully set forth in my copending application, Serial #463,141, filed June 23, 1930 which issued September 27, 1932 as Patent No. 1,879,882. The present invention is directed more particularly to the improvements 10 pointed out in the accompanying claims.

It will be understood that the embodiment of the invention herein described and illustrated is merely a convenient form of the invention. Many changes and modifications may be made therein 15 without departing from the spirit and scope of the appended claims.

What I claim as new and desire to protect by Letters Patent of the United States is:—

1. In a switch of the character described, a 20 switch frame, including a pair of insulating plates and a plurality of posts for positioning said plates, means for connecting a conductor to one of said posts, a switch mechanism for electrically connecting and disconnecting said post and a second 25 post, and a center contact attached to one of said plates by said second post.

2. In a switch of the character described, a pair of insulating plates, a plurality of posts for positioning said plates, means for connecting a conductor to one of said posts, a switch mechanism supported between said plates for electrically connecting and disconnecting said post and a second post, a center contact having an arm secured to said second post, a screw shell mounted 30 on one of said plates, a horseshoe terminal having a plurality of lugs, two of said lugs being bent over said plate to secure the screw shell thereto, and a third lug having means for connecting a conductor thereto for making electrical connection with said screw shell.

3. In a switch of the character described, a switch frame, including a pair of insulating plates and a plurality of posts for positioning said plates, a screw shell, a horseshoe terminal for securing 45 said screw shell to one of said plates, the open side of said horseshoe terminal overlying the end of one of said posts, and a center contact having an arm extending into the open side of 50 said horseshoe terminal and secured to the end of said post.

4. In a switch of the character described, a switch frame including a pair of insulating plates and a plurality of posts for positioning said plates, a screw shell, a horseshoe terminal for securing said screw shell to one of said plates, the open side of said horseshoe terminal overlying the end of one of said posts, a center contact having an arm extending into the open side of the horseshoe 60 terminal and secured to the end of said post, a switch mechanism mounted between said plates for electrically connecting and disconnecting said post and a second post, said second post serving 65 as a terminal for connection to an electric circuit, the horseshoe terminal having a lug forming a second terminal for connection to an electric circuit.

RUDOLF POPP.
